UNITED STATES PATENT OFFICE.

VICTOR BÈLANGER, OF SEAVIEW, MASSACHUSETTS.

SPINDLE.

SPECIFICATION forming part of Letters Patent No. 768,724, dated August 30, 1904.

Application filed April 12, 1902. Serial No. 102,543. (No model.)

To all whom it may concern:

Be it known that I, VICTOR BÈLANGER, of Seaview, Marshfield, in the county of Plymouth and State of Massachusetts, have invented certain new and useful Improvements 5 in Spindles, of which the following is a specification.

This invention has relation to spinning and twisting machinery, and more particularly to 10 the spindles which are employed therein and the mechanism by which power is transmitted from the drum to the spindle-blade.

The spindle is usually equipped with a whirl, around which passes an endless tape, cord, or 15 band driven by a drum or cylinder. The whirl and the drum bear the greatest possible diametrical ratio with relation to each other in order that the spindle may be rotated at the highest speed consistent with a given speed 20 of the drum and the distance between said parts, which is necessarily limited owing to the character of the machine and the space occupied thereby.

It has been found from practical experience 25 that it is not desirable to increase the speed of the drum over a certain number of turns per minute, since by reason of the construction of the drum, its length, and the wear of the bearings the drum causes the vibration of 30 the frame and effects a serious deterioration in the quality and strength of the yarn produced. The vibration of the frame causes the saddle-weights to dance, whereby the pressure of the top rolls constantly varies and 35 causes the formation of thick and thin spots in the roving and causes the traveler to move unevenly about the ring, whereby the yarn is unevenly built upon the bobbin and is frequently broken.

40 The object of the present invention is to provide mechanism by which the speed of the spindle-blade may be materially increased without increasing the speed of the drum or by which the speed of the drum may be decreased without a corresponding decrease in 45 the speed of rotation of the spindle-blade. In accomplishing this object I remedy the evils which have attended the attempt to increase the production of a frame by an increase in

the speed of rotation of the spindles, as here- 50 inbefore described.

The invention consists in certain features of construction and relative arrangement of parts, as recited in the claims, the drawings illustrating and the specification describing 55 one form of mechanism in which the invention is embodied, but to the details of construction of which the invention is in no wise limited.

On the said drawings, Figure 1 represents 60 in plan view a portion of a spindle-rail with one form of my invention mounted thereon. Fig. 2 represents a front elevation of the same with one of the spindles in section. Fig. 3 represents a section on the line 3-3 of Fig. 2. 65

The spindle-rail is indicated at *a* and is apertured at intervals to receive the spindle-casings. Each spindle consists of a hollow casing *b*, flanged, as at *b'*, to rest upon the rail and threaded, as at *b''*, to receive a nut *c*, which 70 coacts with the flange *b'* in clamping it adjustably to the rail. Within the casing is placed a bolster *d*, and between the reduced lower portion thereof and the inner wall of the casing is a sleeve-like layer of fibrous material. The 75 lower end of the bolster is held yieldingly against rotation by the usual means, the spindle as thus far described differing in no essential from those now in general use.

The blade is indicated at *e*, and it has the 80 usual tapering upper and lower ends. It is rotatively mounted in a sleeve *f*, located between it and the bolster and having a tapering socket to receive said blade. An oil-space is formed between the ends of the sleeve, and 85 provision is made for the access of oil thereto from the casing, to which oil is supplied from the cup *g*. The sleeve is adapted to rotate within the bolster, and it projects upward far enough to receive two pulleys *f'* *f''*, which 90 may be formed integrally therewith. If formed separately, said pulleys are secured to said sleeve to rotate therewith. To the blade is attached a whirl or pulley which is less in diameter than either of the pulleys *f'* *f''* and 95 which is located directly above them, as shown in Fig. 2.

The pulley *f''* receives the tape, cord, or

band h , which is driven by the usual drum or cylinder, (not shown,) and between the pulley f' of one spindle and the pulley or whirl e' of the next adjacent spindle is stretched a cord or other endless flexible connection i . Assuming that the ratio of the pulleys f' and e' are as two to one and that the pulleys f', f'' are equal in diameter and are also equal in diameter to the whirl now commonly employed, it will be apparent that when the drum is rotated at a speed sufficient to rotate the pulley f'' at nine thousand turns per minute the spindle-blade of the next adjacent spindle, driven from the pulley f' , will be rotated at eighteen thousand turns per minute, or twice the speed attained when the usual construction is followed.

The stoppage of one blade in "piecing-up" or in doffing does not retard the rotation of the blade on either side thereof, since the band will slip on the whirl e' thereon, and the pulleys f' and f'' are entirely independent thereof. The blade rotates within the sleeve, and the sleeve rotates within the bolster, and they are independent of each other. The blade and the sleeve of each spindle are held against accidental axial movement by the latch j on the cap j' of the oil-cup.

This construction of driving mechanism requires the employment of an extra spindle or an extra pair of pulleys f', f'' at the end of each row of spindles; but it does not necessitate an increase in the driving-bands h .

If desired, the connections i may be expandable and contractile in order to compensate for adjustment of the spindle-casings relatively to each other.

Having thus explained the nature of the invention and described a way of constructing and using the same, although without attempting to set forth all of the forms in which it may be made or all of the modes of its use, I declare that what I claim is—

1. In combination, a rail, a spindle on said rail having a whirl of relatively small diameter thereon, a driving-band, a rotary member of relatively large diameter supported on said rail, said rotary member being actuated by said band, and having its axis substantially parallel to the axis of said spindle, and power-transmitting means between the rotary member and the said whirl in consequence of which the spindle is driven by the rotary member at a relatively higher speed than if driven directly by said band in the usual manner.

2. In combination, a rail, a spindle on said rail having a whirl of relatively small diameter thereon, a driving-band, a rotary member of relatively large diameter supported on said rail, said rotary member being actuated by said band, and having its axis substantially parallel to the axis of said spindle, and a second band connecting said rotary member and said whirl whereby the latter is driven by the former at a relatively higher speed than if driven directly by said band.

3. In combination, a rail, a spindle on said rail having a whirl of relatively small diameter, a rotary member of relatively larger diameter rotating said whirl at a higher speed than its own, a driving-band, and a grooved pulley fast with said rotary member and rotating the same, said grooved pulley being not less in diameter than said rotary member.

4. In combination, two casings, a sleeve rotatable in each casing, a blade rotatable in each sleeve, a power-transmitting device connecting the sleeve in one casing with the blade in the other casing.

5. In combination, a series of spindles, each comprising a blade, an independently-rotatable sleeve, and a casing, means for rotating each sleeve independently of the other sleeves, and a power-transmitting connection between the sleeve of one spindle and the blade of the next adjacent spindle.

6. In combination, a series of spindles, each comprising a blade, an independently-rotatable sleeve, a whirl on the blade and a pair of pulleys on the sleeve, a separate band engaging one pulley on each sleeve for rotating it independently of the others, and an endless band connecting the other pulley on each sleeve with the whirl on the blade of the next adjacent spindle.

7. In combination, a rail, a driving-band, a spindle-blade, and speed-multiplying power-transmitting mechanism interposed between the said band and the said blade in consequence of which the said blade is driven at a speed greater than if the blade were driven directly by said band, said mechanism including a band-driven member having its axis substantially parallel to the axis of the blade.

In testimony whereof I have affixed my signature in presence of two witnesses.

VICTOR BÉLANGER.
